UNITED STATES PATENT OFFICE.

MERTON P. STEVENS, OF EAST ORANGE, NEW JERSEY.

AUTOMATIC PRESSURE-OPERATED VALVE.

1,060,142.

Specification of Letters Patent.

Patented Apr. 29, 1913.

Application filed November 20, 1911. Serial No. 661,277.

To all whom it may concern:

Be it known that I, MERTON P. STEVENS, a citizen of the United States, residing at East Orange, in the county of Essex and 5 State of New Jersey, have invented certain new and useful Improvements in Automatic Pressure-Operated Valves, of which the following is a specification.

My invention relates to new and useful 10 improvements in automatic pressure-operated valves, and more particularly contemplates a valve adapted to be placed in a conduit for distributing fluid or gas under pressure from a suitable source or supply 15 to a point or points of use, and which will be constructed to automatically shut off the supply upon a reduction of pressure in the distributing conduit or the system fed thereby, such for instance as might be caused by 20 a leak or breakage of parts of said conduit or system.

Broadly the invention contemplates the application of the valve to any part of the system, for instance it may be so constructed 25 as to constitute the coupling, or be associated with the coupling which connects the distributing conduit to the supply tank or reservoir, or it may be interposed in the conduit or system at a point more or less 30 remote from the source of supply. When the invention is applied as in the first case just described the valve may also serve as an inlet valve through which the tank or container may be filled.

The object of the invention is to provide 35 a valve of the character set forth which will be simple in construction, inexpensive of manufacture, and which will effectually accomplish the purposes for which it is devised.

I have fully and clearly illustrated my invention in the accompanying drawings to be taken as a part of this specification, and wherein—

Figure 1 is a view in side elevation of one embodiment of my invention; Fig. 2 is a longitudinal section through a valve of the form shown in Fig. 1; Fig. 3 is a longitudinal section through the valve of Fig. 1, 45 showing the same in cut-off position; Fig. 4 is a view in longitudinal section showing the valve in filling position; Fig. 5 is a longitudinal section of another embodiment of the same invention; Fig. 6 is a longi-

tudinal section of the embodiment of the 55 valve shown in Fig. 5, with the parts in cut-off position.

Referring to the drawings by characters of reference, and particularly to Figs. 1 and 2, in which the valve is shown in connection 60 with a supply tank; 1 designates in section a wall of a storage or supply tank which need not be fully illustrated and described as in itself it forms no part of my present invention, except in so far as it may enter 65 into combination with other parts. This tank may be of any suitable material and construction and it is formed with an interiorly threaded opening 2, through a wall thereof, which receives a threaded plug 3, 70 having a reduced portion 3^a to extend within the tank and a longitudinal bore 4. At its outer end it may be provided with a nut head 5 to be engaged by a wrench in inserting and removing the plug from the thread- 75 ed opening 2. At a point intermediate its ends and within the bore 4 is a transverse diaphragm 6, having passageways 7 and a central guide opening 8, all for a purpose to be presently set forth. The innermost end 80 of the plug 3, is formed with a nipple or reduced portion 9 surrounded by a shoulder 10, the extreme inner end of said plug being cut off square to form an annular seat 10^a with which co-operates a valve to be pres- 85 ently described. Surrounding the nipple 9 seated against the shoulder 10 is a cylindri- 90 cal tube 11, an air and fluid tight connection being made between said tube and the plug, and the seat 10^a being located inside the tube. 95 This tube constitutes a valve chamber in which moves a piston valve 12, from the opposite faces of which project plunger rods 13, 14, the former being guided in the guide opening 8, and the latter in an opening 15 100 in a plug 16 threaded into the inner end of the chamber and closing the same. Surrounding the rods 13, 14, are expansive 105 springs 13^a, 14^a, the former abutting the dia- phragms 6 and one face of the valve, while the latter abuts the other face of the valve, and said plug 16, and both exerting their forces expansively to hold normally the valve in substantially the position shown in Fig. 2. The piston valve 12, when in nor- 105 mal position is located at a point interme- diate the ends of the chamber and divides the latter into two chambers, one of which,

indicated at 17, communicates with the outlet bore of the plug 3, and the other of which constitutes a pressure chamber 18, in which the rear face of the piston valve is exposed to the pressure of the tank. In this chamber 17, which communicates with the bore of the plug 3, is an inlet opening 19 which is normally uncovered by the piston valve, and through which the fluid or gas from the tank may enter the chamber 17 and pass to said bore, and in rear of the piston valve the chamber 18 is formed with two sets of openings 19^a, 20, respectively, the former being located adjacent the rear face of the valve and the latter adjacent the rear end of the chamber where they cannot be closed by the valve.

During the normal operation of the valve the parts are in the position shown in Fig. 1, the valve being held in this position by the opposing springs 13^a, 14^a, so that the valve is in rear of the opening 19 and the latter is uncovered, giving free access of the contents of the tank to the chamber 17 to flow through the bore of the plug 3. When the parts are in this position the contents of the tank flow freely through the opening 19 and the bore of the plug 3 to the conduit or system, and as long as the latter remains intact the valve will maintain the position shown in Fig. 2, but should the pressure in the system drop suddenly for any reason, the higher pressure of the contents of the tank acting on the rear face of the valve 12 in the chamber 18 will force the valve 12 toward the annular valve seat 10^a, first operating to cover the opening 19 to stop flow of fluid or gas to the chamber 17, and then engaging said annular valve seat 10^a to completely shut off communication between the plug 3 and the tank, as shown in Fig. 3. The openings in the chamber 18 are preferably of such size that the fluid or gas may always have free access to said chamber. The same operation takes place when the distributing pipe is disconnected from the tank, the valve in this case automatically operating to close exit of the contents of the tank.

The face of the valve is preferably made of leather, rubber or similar material, and the face of the valve seat 10^a is corrugated so that a fluid and gas tight engagement may be made between the valve and seat.

As heretofore stated the valve just described is efficient as a charging valve when the tank is to be filled. In this instance the filling tube is connected to the coupling 3, and the greatest pressure being on the face of the valve 12 toward the seat 10^a, the valve 12 will be forced back until it uncovers the ports 19^a, so that the gas or fluid may freely enter the tank. I preferably make these openings 19^a of such area that the fluid or gas may flow freely to the tank.

When the filling tube is disconnected from the coupling 3 the valve 12 seats on the seat 10^a to cut off flow from the tank. After the valve has closed, due to a leak in the distributing pipe, or the escape of gas therefrom, upon stopping said leak or escape the distributing pipe becomes a chamber sufficiently confined so that leakage by the valve from the tank into the distributing pipe will raise the pressure in said pipe, and the valve chamber to move the piston valve to uncover the port 19 and permit free passage of the gas from the tank to the distributing pipe.

The embodiment of the invention above described is a form of the invention adapted for connecting a conduit with a tank and I will now proceed to describe a form adapted to be inserted at any desired point in a pipe line.

Referring particularly to Figs. 5 and 6, 21 designates a coupling adapted to be inserted in a pipe line having threaded sockets 22, 23, respectively, the former of which is adapted to receive an inlet pipe 24, and the latter an outlet pipe 25. This coupling is provided at one end with a threaded socket 26 and an annular shoulder 27 which receives a plug 28 in threaded engagement with said socket and abutting said shoulder, said plug projecting at its inner end into an enlarged chamber 29 which communicates at its opposite end through an opening 30 with the inlet pipe. At its inner end said plug is provided with an annular valve seat 31, and a transverse diaphragm 32 formed with ports 33 and a central guide opening 34 for a purpose to be presently described. At the inner end surrounding the valve seat the plug is reduced to form a shoulder 35, and at this reduced end portion, surrounding the valve seat and abutting said shoulder, is a cylindrical jacket 36 having an end wall 37 formed with a port 38 opening toward the inlet pipe. In the side wall of this jacket intermediate the valve seat and said end wall is an inlet port 39, with which co-operates a piston valve 40 having a plunger rod 41 guided in the guide opening of the diaphragm in the plug, and surrounding this rod is an expansive spring 42 which abuts the diaphragm and the piston valve to normally hold the latter in position to uncover the inlet opening so that the latter may communicate through the interior of the jacket with the ports in the diaphragm of the plug. It will be understood that the piston valve closely fits the interior of the jacket and normally divides the same into two chambers, one of which is in communication with the outlet plug and the other of which constitutes a pressure chamber so that the rear face of the valve, or that away from the valve seat, is exposed to the pressure of the fluid in the inlet pipe and the enlarged chamber of the coupling.

The spring heretofore described operates to normally hold the piston valve in position to uncover the inlet so that fluid or gas from the chamber of the coupling may flow into the outlet chamber and thence through the diaphragm to the outlet pipe. In order to control the area of the inlet opening I may provide a valve, which for purposes of simplicity is shown as consisting of a screw plug inserted through a threaded opening in the casing having a conical end adapted to coöperate with said inlet to enlarge or reduce the area of the same opening to the flow of the fluid or gas.

The normal position of the valve is that shown in Fig. 4, and while the valve is in this position the gas or fluid is free to flow from the inlet pipe, through the coupling, the inlet opening, the outlet chamber of the diaphragm to the outlet pipe, and its flow is possible as long as the pressure in the outlet pipe is sufficient to permit the spring to hold the valve in the position shown. Should the pressure in the outlet pipe be reduced, as for instance by breakage of the pipe, or a leak, the excess of pressure in the pressure chamber over the combined force of the spring and the pressure on the outlet side of the valve will operate to urge the valve to its seat, whereby flow from the inlet to the outlet pipe is cut off.

What I claim and desire to secure by Letters Patent of the United States is:—

1. A valve of the class described comprising a tubular casing, a piston valve in the casing and closely fitting the same and thereby separating the same into two chambers out of communication with each other through the casing, one of said chambers having an outlet and a valve seat with which the valve is coöperable to control said outlet, said outlet chamber having an inlet in its side wall opening exterior to the casing adapted to be covered and uncovered by the side face of said valve, and the chamber on the opposite side of the piston valve having an inlet opening exterior to the casing.

2. A valve of the class described comprising a tubular casing, a piston valve in the casing and closely fitting the same and thereby separating the same into two chambers out of communication with each other through the casing, one of said chambers having an outlet and valve seat with which the valve is coöperable to control said outlet, said outlet chamber having an inlet in its side wall opening exterior to the casing and adapted to be covered and uncovered by the side face of the said piston valve, and the chamber on the opposite side of the valve having an inlet opening exterior to the casing, and means for urging the piston valve to a position to uncover the inlet to the outlet chamber.

3. A valve of the class described compris-

ing a tubular casing, a piston valve in the casing and closely fitting the same thereby separating the same into two chambers out of communication with each other through the casing, one of said chambers having an outlet and a valve seat with which the valve is coöperable to control said outlet, said outlet chamber having an inlet in its side wall opening exterior to the casing and adapted to be covered and uncovered by the side face of said piston valve, and the chamber on the opposite side of the valve having an inlet opening exterior to the casing, and a spring for urging the piston valve away from said outlet to a position to uncover the inlet to the outlet chamber.

4. A valve of the class described comprising a tubular casing, a piston valve in the casing and closely fitting the same and thereby separating the same into two chambers out of communication with each other through the casing, one of said chambers having an outlet and a valve seat with which the valve is coöperable to control said outlet, said outlet chamber having an inlet opening exterior to the casing and adapted to be covered and uncovered by the side face of said piston valve, and the chamber on the opposite side of the valve having an inlet opening exterior to the casing, and a spring in each chamber to determine the position of the valve relative to the chamber inlets.

5. A valve of the class described comprising a tubular casing, a piston valve in the casing separating the same into two chambers, one of the chambers having an outlet surrounded by an annular valve seat with which the valve is adapted to coöperate, an opening through the wall of the chamber having the outlet adapted to be covered and uncovered by the valve, the wall of the chamber on the opposite side of the piston from the outlet chamber being also provided with an opening of greater area than said first-named opening, and springs acting to normally hold the valve away from its seat and clear of the opening through the wall of the outlet chamber.

6. A valve of the class described comprising a tubular casing, a piston valve in the casing dividing the same into two chambers, one of said chambers having an outlet surrounded by an annular valve seat with which said piston coöperates, an opening through the casing wall of the outlet chamber adapted to be covered and uncovered by the valve, an inlet through the wall of the opposite chamber, rods connected to the valve and projecting longitudinally of the said chambers, and springs on said rods engaging the piston and abutments in the chambers respectively to normally maintain said valve in position to uncover the inlet to the outlet chamber.

7. A valve of the class described compris-

ing a coupling member having a longitudinal bore, a sleeve mounted on the coupling and surrounding the same, the surrounded portion of the coupling constituting an annular valve seat, a piston valve movable longitudinally of said sleeve and normally dividing the same into two chambers, one of which is provided with an inlet through its wall communicating through the sleeve with the bore of said coupling, and the other chamber provided with an inlet, and means whereby a reduction of pressure on the coupling side of the piston will move the piston to close the inlet opening to the outlet chamber.

8. In combination a tank, a valve opening through the tank wall comprising a casing, a piston valve separating the casing into two chambers, one of which has an outlet through the tank wall surrounded by an annular valve seat with which said valve is coöperable, said outlet chamber having a port opening into the tank, and the chamber on the opposite side of the valve from the outlet having a port opening into the tank.

9. A valve of the class described comprising a casing shell, a piston valve within the shell and closely fitting the same, and dividing the shell into two chambers, one of which is provided with an outlet and a valve seat concentric with the shell, with which seat the valve is coöperable, the chamber on the outlet side of the piston valve having an inlet, and the chamber on the opposite side of the valve having an opening.

10. In combination a tank, a valve casing opening through the tank wall, a piston valve separating the casing into two chambers, one of which has an outlet through the tank wall surrounded by an annular valve seat with which said valve is coöperable, the chamber on the outlet side of the valve having an opening into the tank, and means whereby the opposite side of the piston from

the outlet is subjected to the pressure of the tank.

11. In a valve of the class described, a casing having an outlet, and an inlet through the casing wall communicating with said outlet, and a filling passage independent of the said inlet, said filling passage also communicating with the outlet, means for controlling communication between said inlet and the outlet and the filling passage and the outlet, means for normally operating said first-named means to establish communication between the inlet and the outlet and to cut off communication between said filling passage and the outlet, said first-named means being pressure operated to establish communication between the filling passage and the outlet.

12. A valve of the class described comprising a casing, a piston valve within the casing and closely fitting the same and dividing the same into two chambers, one of which is provided with an outlet and a valve seat with which seat the valve is coöperable to control said outlet, the chamber on the outlet side of the piston valve having an inlet, and the chamber on the opposite side of the valve having an opening communicating with the interior thereof.

13. A valve comprising a casing having a passage serving as a combined inlet and outlet, means to normally cause a restricted flow outward from the casing through the combined inlet and outlet, and pressure-controlled means for permitting an increased flow inward through the combined inlet and outlet when the same is employed as an inlet.

In testimony whereof I have hereunto signed my name in the presence of two subscribing witnesses.
